[57] CLAIM

The ornamental design for a dog chew toy, as shown
and described.

DESCRIPTION

FIG. 1 is a perspective view of a dog chew toy showing
my new design;

FIG. 2 is a top plan view thereof, the bottom plan view
being identical;

FIG. 3 is a left side elevational view thereof;

FIG. 4 is a front elevational view thereof;

FIG. 5 is a rear elevational view thereof;

FIG. 6 right side elevational view thereof;

FIG. 7 is a perspective view of a first alternative em-
bodyment of the dog chew toy of FIG. 1;

FIG. 8 is a perspective view of a second alternative
embodiment of the dog chew toy of FIG. 1; and,

FIG. 9 is a perspective view of a third alternative em-
bodyment of the dog chew toy of FIG. 1.

The opposite side of the bone seen in FIGS. 8 and 9 is
identical to the bone shown in FIG. 1.

FIG. 1.

FIG. 3.

FIG. 4.

FIG. 2.

FIG. 5.

FIG. 6.

FIG. 7.

FIG. 8.

FIG. 9.
